UNITED STATES PATENT OFFICE.

ARTHUR B. HENDERSON, OR HURLEY, NEW MEXICO.

WORK HOLDER.

1,421,280.

Specification of Letters Patent. Patented June 27, 1922.

Application filed April 28, 1921. Serial No. 465,311.

To all whom it may concern:

Be it known that I, ARTHUR B. HENDERSON, a citizen of the United States, and resident of Hurley, in the county of Grant and 5 State of New Mexico, have invented a new and Improved Work Holder, of which the following is a full, clear, and exact description.

My invention relates to a work holder such 10 as is particularly adapted for use in connection with hand work, and aims primarily to provide a device of this character which shall be in the nature of a crochet guide.

It is well appreciated in connection with 15 crocheting work, that considerable difficulty has been experienced in making a design, in that the operator usually experiences trouble in placing all parts of the design which should be aligned properly with respect to 20 each other and the material being worked.

Furthermore this difficulty is aggravated, 25 incident to the fact that the goods being worked creases and folds so that all portions of the same adjacent the points being worked are invisible unless the operator continuously strengthens the material.

With this in view my present invention aims to provide a guide particularly adapted 30 for use in connection with crocheting work, and the primary object of this invention is that of constructing a guide by means of which even an amateur will be capable of properly aligning all parts of the design.

A further object of this invention is the 35 construction of a device of the character stated which will retain the goods in such a manner that points adjacent those parts of the surface being worked upon will at all times be visible.

40 Further objects of my invention will appear in the annexed specification taken in connection with the drawings which latter present one practical embodiment of the same, and in which;

45 Figure 1 is a plan view of my device and showing the same in use.

Figure 2 is a sectional side view of the parts as illustrated in Figure 1, and

50 Figure 3 is a transverse sectional view of the device as illustrated in Figures 1 and 2.

In these views the reference numeral 5 indicates the goods to which the design 6 is being applied, and with which, as aforesaid, difficulty has been experienced in properly aligning portions of the design, as 55 well as retaining the goods in such a manner that all of the portions of the same adjacent the points being worked will be visible to the operator.

Referring now more particularly to the 60 guide by means of which these results are accomplished it will be seen that the same includes a pair of bars 7 which are formed with longitudinally extending openings 8 the approaches of said openings being preferably inclined as has been indicated by the reference numeral 9 for a purpose herein- 65 after more fully specified.

The goods 5 is disposed between the bars 7 and is retained in this position by clamping 70 the bars one to the other by means of wing nuts 10 co-operating with bolts 11, projecting through each of the bars.

The structure presented will obviously prevent any accidental movement on the 75 part of the goods 5 with respect to the bars and it will be obvious, as has been illustrated in Figure 1 that the openings 8 will serve to at all times provide a guide by means of which the operator is incapable of working 80 in other than a perfectly aligned position. Furthermore the inclined approaches 9 constitute a natural guide which will serve to divert a carelessly presented needle towards the opening 8. 85

Furthermore by forming the bolts 11 with extended end portions 12 it will be appreciated, as has been indicated in Figure 3 that the entire device may be rested upon a supporting surface 13 in which position it will 90 be presented in such a manner that ready access may be had to those portions of the goods 5 which are to be worked upon.

Thus I have provided a guide particularly adapted for use in connection with crochet 95 work, and which will obviously overcome the objections noted in the preamble, of this specification, it being also seen that an article constructed in accordance with my invention may be manufactured at a minimum 100

of cost and will present few parts thus reducing the danger of breakage or inoperativeness.

Obviously numerous modifications of 5 structure might readily be resorted to without departing from the spirit of my invention, which I claim as;

1. A work holder, including a bar formed with a longitudinal opening having in-

wardly inclined walls, and means for retaining a piece of goods in engagement with one of the faces of said bar.

2. A work holder including a pair of bars formed with longitudinally extending openings having inwardly inclined walls, bolts 15 extending through both of said bars and wing nuts mounted upon said bolts.

ARTHUR B. HENDERSON.
